(57) **CLAIM**

The ornamental design for a framing system for use with silicone edge graphics, as shown and described.

DESCRIPTION

FIG. 1 is a top front left isometric view of a framing system for use with silicone edge graphics showing our new design; FIG. 2 is a top elevation view thereof, the bottom elevation being a mirror image thereof;

FIG. 3 is a front elevation view thereof;

FIG. 4 is a back elevation view thereof;

FIG. 5 is a left side elevation view thereof; and,

FIG. 6 is a right side elevation thereof.

The framing system for use with silicone edge graphics is shown with symbolic break in its length. The appearance of any portion of the framing system for use with silicone graphics between the break lines forms no part of the claimed design.
